LAST

Henry F. Loewer, Rochester, N. Y., assignor to
 United Last Company, Boston, Mass., a corpora-
 tion of Maine

Application April 18, 1938, Serial No. 202,589

4 Claims. (Cl. 12—136)

This invention relates to hinge lasts and is disclosed as embodied in a last designed especially for relasting. It is well known that it is often difficult to remove a last from a shoe and that it is considerably more difficult to get it back in the shoe again.

It is a principal object of this invention to provide a last which can be easily removed from or replaced in a shoe without the use of special machinery.

The last of the present invention is in two parts severed by a cut having a cylindrical portion concave forwardly, and joined by a pivotally pinned link which lies oblique to the cylindrical portion when the last is in extended position.

When collapsing the last the heel part is turned upwardly and forwardly about the axis of the cylindrical portion, and simultaneously separates from the forepart owing to the obliquity of the link, which during this movement approaches a position normal to the cylindrical portion. The clearance thus formed between the last parts permits the heel part to swing downwardly and backwardly about the rear link pin so that the lower portion of the heel part, which is the troublesome portion of the heel part to get out of or into the shoe, is carried forward to a substantial extent and therefore does not tend to bind in the back of the shoe.

Preferably, and as herein illustrated, a notch is formed on the forepart of the last, interrupting the cylindrical portion of the cut, to accommodate the lower front corner of the heel part and increase the amplitude of the latter described movement.

Conveniently, also, resilient means are provided to hold the last impositively in both extended and collapsed positions.

These and other features of the invention comprising certain combinations and arrangements of parts will be apparent from the following description of a preferred embodiment of the invention shown in the drawing, in which

Fig. 1 shows the last in extended position; and Fig. 2 shows the last in collapsed position.

The illustrated last is divided by a cut comprising a cylindrical portion 10 having its axis at 12 in front of the cut, a short horizontal plane portion 14 serving to prevent relative twisting of the last parts, and a plane portion 16 sloping somewhat downwardly to the rear and intersecting the tread face of the last. In manufacture the portion 14 is broken after the portions 10 and 16 are sawed. The last parts are drilled for

two pins 18, 20 and a bonding link 22 is mounted on the pins. The link 22 has two cam portions 24 and 26 on its rear and front ends respectively. These cam portions cooperate with two balls 28, 30, respectively, which, by virtue of the 5 springs 32, 34, resiliently hold the link and last parts against movement from the positions shown in both Figs. 1 and 2. These cam portions are in the form of extensions which lie farther from the centers of the pins 18, 20 than do those portions of the ends of the link that lie on each side of the cam portions. The balls 28, 30 pass from one side of the cam portions to the other when the link swings in manipulating the last.

The secant face formed on the forepart by the 15 cylindrical cut 10 is interrupted by a notch 36 cut across it from side to side after the severance of the heel part.

When it is desired to collapse the last the heel part is swung upward and forward. The axis 20 of the link 22 is oblique to or non-radial of the cut 10, at the place where it crosses the cut, as seen in Fig. 1, so that this movement, which brings the axis of the link toward a position normal to the cut 10, will separate the heel part 25 from the forepart, thus providing clearance for the heel part to swing on the pin 18. As the collapsing movement is continued the heel part is swung clockwise around the pin 18 until its lower front corner 38 lodges in the notch 36, 30 as shown in Fig. 2. Meanwhile the balls 28, 30 slide over to the other sides of their cooperating cam portions on the link. The last is then easily removed from a shoe 40 since the lower part of the heel part is so far forward that it easily 35 spreads the counter and slides out.

In relasting the shoe this process is reversed. The last is easily put into the shoe in the Fig. 2 position, after which a pressure by the operator's thumb on the cone at 42 assisted immediately 40 after its beginning by the spring-pressed balls 28, 30 and the cam portions 24 and 26 will reverse the described movement of the heel part and the lower rear corner of the heel part will follow the arrow in Fig. 2 back to the Fig. 1 45 position.

It will be observed that no positive locking means is necessary to hold the last in the Fig. 1 position under manufacturing stresses, such as that of the leveling operation.

Having described my invention, what I claim as new and desire to secure by Letters Patent of the United States is:

1. A last having a heel part and a forepart divided by a generally cylindrical cut having its 55

- axis located in front of the cut and forming opposed secant faces on the last parts, an anchor pin in each last part, a bonding link having circular holes near its ends fitting said pins, said link lying non-radially of the cylindrical cut when the last is in extended position, whereby the last parts will separate when the heel part is swung upwardly and forwardly about the axis of the cylindrical cut to permit a simultaneous downward and backward swing of the heel part to bring its lower front corner against the secant face of the forepart in collapse.
2. A last having a heel part and a forepart divided by a cut having an upper cylindrical portion concave forwardly and a lower plane portion intersecting the tread face of the last, a bonding link pivotally pinned to both last parts and having circular motion only, relatively thereto, the axis of the link being non-radial to the cylindrical portion of the cut when the last is in extended position, whereby when the heel part is swung upwardly and forwardly about the axis of the cylindrical portion it separates from the forepart to permit its rear end to swing downwardly and backwardly to bring its lower front corner to rest against the secant face of the forepart, a cam portion on each end of the link, and a spring-pressed ball mounted in each last part to cooperate with the correspond-
- 5 10 15 20 25 30
- ing cam portion to hold the last in extended and collapsed positions.
3. A last having a heel part and a forepart divided by a cut having an upper cylindrical portion concave forwardly and a lower plane portion intersecting the tread face of the last, and a bonding link pivotally pinned to both last parts, the secant face on the forepart being interrupted by a notch, whereby the heel part may swing upwardly and forwardly about the front link pivot and downwardly and backwardly about the rear link pivot to bring the lower front heel part corner into said notch.
4. A last having a heel part and a forepart divided by a cut having an upper cylindrical portion concave forwardly and a lower plane portion intersecting the tread face of the last, a bonding link pivotally pinned to both last parts, the cylindrical portion on the forepart being interrupted by a notch, whereby the heel part may swing upwardly and forwardly about the front link pivot and downwardly and backwardly about the rear link pivot to bring the lower front heel part corner into said notch, a cam portion on each end of the link, and a spring-pressed ball mounted in each last part to cooperate with the corresponding cam portion to hold the last in extended and collapsed positions.
